UNITED STATES PATENT OFFICE.

DANIEL B. BOON, OF ROSEBURG, OREGON.

CAN OPENER.

Application filed September 19, 1921. Serial No. 501,609.

To all whom it may concern:

Be it known that I, DANIEL B. BOON, a citizen of the United States, residing at Roseburg, in the county of Douglas and State of Oregon, have invented new and useful Improvements in Can Openers, of which the following is a specification.

This invention relates to can openers and has for its object the provision of a can opening machine designed primarily for use in hotels, restaurants, ships, barracks, and other places where a large number of cans must be opened in a short time, the construction of the device being such that a can may 10 be opened at one stroke of a lever, the machine being equally well adapted for use regardless of the size or shape of the cans to be opened.

The essential feature is the provision of a 20 centering member for holding the cans in proper position to be engaged by the cutter, the centering member being so constructed as to hold a can to prevent it from being drawn upwardly in case the cutter sticks in 25 the cut edges of the cans.

An additional object is the provision of a machine of this character which will be simple and inexpensive in manufacture, highly efficient in use, easy to operate, durable in 30 service, and a general improvement in the art.

With the above and other objects and advantages in view, the invention consists in the details of construction to be hereinafter 35 more fully described and claimed and illustrated in the accompanying drawings in which—

Figure 1 is a side elevation of my device, Figure 2 is an elevation taken at right 40 angles to Figure 1,

Figure 3 is a horizontal sectional view taken on the line 3—3 of Figure 1,

Figure 4 is a cross sectional view taken immediately above the operating lever, on 45 the line 4—4 of Figure 1,

Figure 5 is a cross sectional view on the line 5—5 of Figure 1,

Figure 6 is a detail longitudinal sectional view through the base and centering guide 50 showing a can engaged in the latter,

Figure 7 is a bottom plan view of the circular cutter,

Figure 8 is a bottom plan view of a square cutter,

Figure 9 is a cross sectional view there- 55 through,

Figure 10 is a side elevation of a straight cutter,

Figure 11 is an end view thereof, and

Figure 12 is a detail perspective view of 60 the centering guide.

Referring more particularly to the drawings, the numeral 15 designates a suitable base which may be disposed at any preferred height and which may be supported by any suitable means as for instance by being secured upon a table, shelf or other support. Secured upon and rising from this base is a standard 16 which is shown as being rectangular in cross section and secured upon 70 which standard in spaced relation to each other, are yokes 17 which are of elongated loop formation and which are riveted to the standard, as shown at 18. Slidable through these yokes is a vertically disposed bar 19 75 which is formed with a plurality of holes 20 for a purpose to be described. Disposed on opposite sides of the standard and pivoted thereto, as shown at 21, are links 22 with the lower ends of which are pivotally connected levers 23 which are pivotally connected with the bar 19 by means of a suitable pin 24 passing through a selected one of the holes 20. The levers 23 are of any desired length and are to be moved to move 80 the bar 19 up and down through the guide yokes 17.

Disposed upon the base 15 is a centering guide for properly centering the can to be opened and it will of course be understood 90 that there must be a set of these centering guides, depending upon the shape and size of cans to be opened. I have shown the centering guide as formed of a suitable plate 26 having its smaller end formed with a slot 95 27 adapted to be slipped onto the lower end of the standard 16. For preventing upward movement of the guide I provide a U-shaped clip 28 which is disposed in straddling relation upon the lower end of the standard and held thereon by a suitable transverse pin 29. It will be seen that the plate 26 is easily slipped under the clip 28. This guide, or the plate 26, has its wider end formed with a recess corresponding to the size and shape 100 of the can to be opened. I have illustrated the plate 26 as provided with a semi-circular recess 30 which is undercut, as shown at

31, to provide a slight overhanging flange which will engage above the small bead B on the end of a can A to be opened. This flange of course operates to hold the can down.

Secured upon the lower end of the member 19 is a cutter which can be of different sizes and shapes, depending upon the cans to be opened. In Figure 7 I have shown 10 this cutter as comprising a circular disk 32 provided centrally with a socket 33 which receives the lower end of the bar 19, this socket being provided with a transverse hole registering with a transverse hole in the 15 lower end of the bar for the reception of the removable pin 34 for holding the cutter member detachably associated with the movable bar 19. This disk 32 is formed with a peripheral flange 35 and carried by the 20 disk is the cutting blade 36 which is sprung into circular form and slipped within the flange 35. The blade is held in place by a plurality of screws 37 which pass therethrough and into the flange. It will be seen 25 that the lower edge of this blade is formed with teeth 38 which are of course pointed and which have their edges sharpened.

In case the device is to be used for cutting square cans, I make use of a centering guide 30 similar to that already described but formed with a rectangular recess instead of the semi-circular recess 30. I also replace the cutter above described with a square cutter including a square disk 39 having a socket 40 35 having engagement upon the lower end of the bar 19 and having a rectangular flange 41 within which is disposed and to which is secured the blade 42 which is square instead of circular.

40 Instead of making either a circular or a square cut, I may make use of the cutter shown in Figures 10 and 11. In this form the cutter includes a block 43 carrying a socket 44 for engagement upon the bar, and 45 having a longitudinal slot 45 within which is secured a straight blade 46.

The operation of the device is as follows: The can to be opened is placed upon the base 15, it being at first necessary to place 50 the proper centering guide plate 26 in position, the selection of the guide plate depending upon the shape and diameter of the can to be opened. I then secure whichever cutter it is desired to use upon the lower end 55 of the bar 19 and adjust the height of the bar 19 to bring the cutter at the desired height with respect to the can A to be cut, it being well known that such adjustment is necessary owing to the variations in the 60 heights of cans. The operator then grasps the lever 23 and presses downwardly upon it which will of course result in downward movement of the bar 19 so as to bring the

cutting blade into penetrating engagement with the top of the can. It will be observed 65 that the flange surrounding the blade extends almost to the base of the teeth and will strike against the top of the can for limiting the insertion of the blade beyond the degree necessary to effect the cutting action. 70 The operator then moves the bar 19 upwardly whereupon the blade will be withdrawn from the can. In case the blade should tend to stick in the cut it will be apparent that the engagement of the bead B on 75 the can within the undercut portion 31 of the guide plate 26 will prevent the can from following the cut upwardly. Owing to the fact that the links 22 are pivotally connected with the standard and that the levers are 80 pivotally connected with these links, it will be apparent that there will be very free movement of the bar 19 without any possibility of binding. The operation is of course the same regardless of which shape of cutter is 85 used except that when the form of the cutter shown in Figures 10 and 11 is employed the practice would be to make two cuts at right angles to each other in the center of the can top.

90 From the foregoing description and a study of the drawings it will be apparent that I have thus provided a simply constructed and consequently inexpensive can opener by means of which a large number 95 of cans of any size or shape may be opened in a remarkably short time, the device thus recommending itself for use anywhere where canned goods are used on a wholesale scale.

100 While I have shown and described the preferred embodiment of my invention, it is of course to be understood that I reserve the right to make such changes in the form, construction and arrangement of parts as will not depart from the spirit of the invention 105 or the scope of the subjoined claim.

Having thus described my invention, I claim:

110 In a can opening machine, a base, an upright rising therefrom and adapted to support the cutter, and centering means for the can for properly positioning the same upon the base, comprising a plate disposable upon the base and slotted for engagement upon the upright, said plate having a semi-circular 115 recess for receiving a can, the recess having its edge under cut to define a flange overlying the bead at the bottom of a can, and a U-shaped clip engaged upon the upright and engaging against the slotted portion of 120 the plate for holding the latter against upward displacement in case of a tendency to lift the can from the base.

In testimony whereof I affix my signature.

DANIEL B. BOON.
